CARL H. RICH, OF WORCESTER, MASSACHUSETTS, ASSIGNOR TO RILEY STOKER CORPORATION, OF WORCESTER, MASSACHUSETTS, A CORPORATION OF MASSACHUSETTS

STOKER TUYÈRE CONSTRUCTION

Application filed July 25, 1927. Serial No. 208,250.

My invention relates to stokers and more particularly to high side wall tuyères of the type shown in the U. S. patent to Blackburn #1,404,568, of Jan. 24, 1922.

5 The high side wall tuyère of the type shown in the Blackburn patent is a box-like structure mounted to rest on the stationary side wall of a retort and to lean against and be fastened to the brick side wall of the furnace. Such a construction is not adaptable to a stoker of the Riley type in which the tuyères are reciprocated longitudinally of the retort. It is, accordingly, one object of this invention to provide a high side wall 10 tuyère construction which may be mounted on the reciprocable side bars of a stoker.

It is desirable to utilize a narrow plate type of tuyère which may be easily manufactured and quickly assembled in the stoker, and it is 15 a further object of this invention to provide a stoker construction in which a series of plates may be utilized for the high side wall tuyères and which will serve efficiently through a long life of usefulness.

20 If a considerable number of such narrow plates are utilized to form the side wall of the stoker, due allowance must be made for expansion and growth of the tuyère plates during the heating and normal usage thereof. The side bars of a stoker ordinarily slope towards the rear and if plates are mounted loosely on such side bars and are of 25 such a size as to permit the necessary expansion and growth, then these plates will slide towards the lower end of the stoker and leave a large air gap at the upper end which will interfere with the efficient operation of the stoker. It is, accordingly, a further object 30 of the invention to provide a construction which will locate the tuyère plates in such a manner that each will be given the proper amount of space within which to expand and 35 grow and there will be no large air gap throughout the extent of the stoker wall.

40 A further object is to provide a plate type of tuyère which will have a long life and particularly to provide one in which the outer 45 portion of the tuyère may burn away and yet

air leakage to any detrimental extent will be obviated.

If a plate type of tuyère is utilized and particularly if it is mounted on a reciprocating side bar, there is a considerable problem 55 involved in so fastening these plates to their support that they may be easily replaced when they burn out.

Further objects of this invention are accordingly to provide a very simple manner 60 of fastening the tuyère plates in position so that it is possible to remove any plate throughout the entire extent of the wall and to replace it without removing other plates or moving them into a different position and, 65 in particular, to provide a construction which will make it possible to fasten such tuyère plates securely to a movable side bar so as to form a rigid structure.

Referring to the drawings which illustrate 70 one embodiment of my invention, and in which like reference numerals indicate like parts:

Fig. 1 is a longitudinal section through a side retort, partly broken away, showing 75 the tuyère plates in elevation;

Fig. 2 is an enlarged section on the line 2—2 of Fig. 1;

Fig. 3 is a perspective view of a group of tuyère plates mounted in position, part being omitted to show the manner of fastening so them to their support;

Fig. 4 is a perspective view of a single tuyère plate;

Fig. 5 is an enlarged plan view of the corrugated supporting plate; and

Fig. 6 is a perspective view of one section of the rear supporting wall which carries the tuyère plates.

In accordance with this invention I provide a tuyère structure which is particularly useful for high side walls, although it may be utilized in other positions in the place of the ordinary tuyères. This comprises a permanently located supporting portion and a series 95 of removable plates arranged thereon in such a manner as to provide a side wall for the fuel bed and feed air thereto. The supporting portion of the tuyère serves as a rear wall to the air feeding passage and is preferably

mounted on the side bar of the stoker, which may be either stationary or reciprocable, and the removable tuyère plates forming the front wall of the air passage are preferably so constructed that they will hook over a portion of the rear wall and interlock therewith in such a manner that each plate will be located in its proper position and yet be permitted to grow and expand during usage. In order to fasten these removable plates, as well as the rear supporting structure, to the side bar of the furnace I provide a constriction which removably bolts the parts to the side bar and at the same time holds the removable plates rigidly and firmly on the rear supporting tuyère wall.

Referring more particularly to the drawings, I have there shown a portion of a side bar 10 of a stoker of the Riley type which is adapted to reciprocate lengthwise of the retort. As will be understood by reference to prior patents in this art, of which the patent to Riley #1,322,822 may be cited as an example, two side bars co-operating with a bottom form a fuel retort and the tuyère blocks are mounted on the tops of the side bars and so arranged that they may reciprocate therewith. The side bars are spaced apart to admit air to the tuyère blocks supported thereby. At the sides of the furnace a single reciprocable bar 10 is located between the stationary retort bottom 11 and the furnace wall 13 which may be of suitable construction. In the particular embodiment illustrated the refractory wall 13 is supported on an angle plate 14, and attached to this is a wall plate 15 of metal which forms a surface against which the reciprocable side bar may slide.

In the form illustrated in the drawings, the tuyère structure comprises a hollow construction made up primarily of two parts, one a support 16 intended to remain permanently in the stoker and the other a set of removable tuyère plates carried by the support which may be replaced as they burn out. As shown, the support comprises a wall 18 which has a smooth rear surface adapted to slide against the front face of plate 15. For the sake of convenience in assembling these parts in the furnace, this support may be made up in several sections and each section is adapted to carry a number of removable tuyère plates thereon. The support is so constructed that it will rest on the top edge of the side bar 10, and for this purpose it is made in the shape of an angle iron having a bottom 19 provided with a groove 20 which interfits with a projecting rib 21 on the side bar 10, thereby locating the back plate 18 and preventing it sliding into the retort. The side bar 10 is provided with a set of spaced ribs 23 which project rearwardly and support on their top edges the bottom 19 of the support 16. The floor plate 19 has an opening 24 therethrough

extending substantially the length of each section so that air may be admitted in large quantities to the tuyères. Strengthening ribs 25 and 26 are provided to connect the wall 18 with the base 19.

Removably mounted on the support 16 are a series of narrow tuyère plates 30 which are so constructed and arranged as to form an air passage between the wall 18 and their fuel supporting outer faces, for admitting air to the fuel bed. Tuyère openings may be provided in the body of each plate but they are preferably formed by grooves 31 in the edges of the plates as illustrated. The plate 30 is so constructed that it will absorb heat readily and conduct it to the cooling air stream passing beneath and therethrough. For this purpose the plate is preferably so constructed as to have a narrow supporting web 32 and a flange 33 against which the fuel body in the retort rests. The flanges 33 in the present embodiment project even distances on opposite sides of the central web portion, but obviously they may project entirely on one side and be L-shaped instead of T-shaped as illustrated.

In the embodiment illustrated the tuyère members are made in two sections; the plate 30 and a lower removable corrugated plate 35, although it will be understood that the removable tuyère sections may be made up in single members extending from the floor 19 to the top of the wall 18. These corrugated or ribbed plates 35 preferably extend the length of the supporting section 16 and have the further purpose of making it possible to change the air distribution throughout the length of the stoker easily without changing the construction of the remaining parts. These may be easily replaced when they burn out. The spaces between the ribs of these plates form further tuyère openings. The upper and lower air openings are staggered, as shown in Fig. 3, so as to cause a more even air distribution and to provide a more uniform thickness of metal in the casting. The corrugations on the plates 35 are preferably arranged at an angle, as illustrated in Fig. 5 so that coal siftings will not readily get into the openings, the angle being so arranged relative to the normal motion of travel of the fuel that siftings will tend to move down out of the corrugations rather than up them. These ribbed plates 35 are preferably made with a central web 36 carrying on its upper and lower surfaces two rows of vertically extending ribs 37 and 38, thereby giving an extensive surface for air cooling these parts. These ribs correspond with parts of the vertical tuyère plates to be described which make it possible for the outer portion of the tuyère members to burn away and there still be a secondary member adapted to support the fuel and prevent extensive air leakage. That is, the outer row

of corrugations 37 supports the fuel initially and transmits air thereto, and the ribs 38 stand as a reserve which will provide tuyères in case the whole outer part of the bar burns away. These plates are mounted on the bottom 19 of the backing by providing the side walls 26 of the backing with inwardly projecting lugs 39 which fit into notches 40 on the ribbed bars 35.

10 The vertical tuyère plates 30 are constructed similarly in that they have two sets of flanges adapted to support the fuel and supply air thereto. The inner flange 42 is a rib spaced some distance from the outer flange 33 and is substantially parallel and co-extensive therewith, this rib having notches 43 corresponding with the tuyère openings 31 so as to transmit the air within the air passage to the outer face of the tuyère. The 15 upper end 45 of the plate 30 is a massive thick section of iron which will withstand considerable burning before its utility is impaired.

16 One of the primary features of my invention has to do with the manner of fastening the tuyère plates and backing to their support so that any individual tuyère plate may be removed without interfering with the others. To this end, I provide means which 20 serves to bolt down a group of these tuyère plates to the side bars and which indirectly fasten the support to the side bar as well, although it will be understood that these parts may be bolted separately and independently to the side bar. However, as illustrated, a single bolting device serves to fasten them both in place. In order that the tuyère plates may be located in proper positions to 25 permit expansion and growth and to prevent the plates from sliding down to the rear of the stoker, I provide the plate 18 with up-standing lugs 48 which are so spaced that the webs 32 of the removable tuyère plates will fit therebetween. The lugs 48 project 30 toward the retort as well as upwardly from the plate 18 so that they are spaced from the plate 15 of the furnace wall. The preferred manner of fastening down the tuyère plates is to hook their tops over these upstanding lugs 48 and to bolt them down so they 35 cannot be lifted from this hooked position. To this end the upper portion 45 of the tuyère plate is provided with a downwardly extending projection or flange 50 which is located on both sides of the web 32, as illustrated, and this flange 50 slips into position 40 between the upstanding lugs 48 and the plate 15. In order to prevent movement of the lower end of the tuyère plate toward the retort, the web 32 extends downwardly to form 45 a projection 53 which is inserted thru the opening 24 in the bottom of the plate 19. It will therefore be seen that I have provided interfitting locating members on the tuyère plates and the support which hold the tuyère 50 plates in position and prevent movement

thereof in every direction except upwardly, and that each tuyère plate can be removed only by lifting it vertically from its operative position.

55 In order to fasten these parts in place and prevent their removal except as desired, I can utilize various types of construction but in the preferred embodiment I provide a rod 55 and a hook bolt 56, which may be secured together if desired. This rod 55 rests on the bottoms 58 of the slots 59 in the webs 32. Each slot 59 is of greater size vertically than the thickness of the rod 55 so that the rod 55 may be raised by lifting any one plate without disturbing the other plates in that group, 60 so as to permit any one of these tuyère plates to be moved upwardly with the rod to a sufficient height to permit the flange 50 to clear the tops of the lugs 48 and to withdraw the lug 53 from the slot 24 in the bottom 19. The lug 53 may be considerably longer than the flange 50 so that it is merely necessary to lift the plate high enough to clear the flange 50, and then the tuyère plate may be tipped toward the retort to move the shoulder 58 out 65 from under the rod 55 and thus permit the tuyère plate to be lifted a further sufficient distance to withdraw the lug 53 from the opening 24. The hook bolts 56 are bolted down to a flange 60 on the side bar and are fastened thereto by means of nuts 61 on the lower ends of the bolts. Before any one of the tuyère plates may be removed it will be understood that the nut 61 should be removed or loosened so as to permit upward motion of 70 the hook bolt 56 and the rod 55. The rod 55 is prevented from being moved endwise by the side plates 26 of the support 16 and the rod is thereby permanently located in position in the assembled group of tuyère plates. The ribs 25, it will be observed, contact with 75 the rod 55 and prevent it from being moved out of the slot 59.

76 The end tuyère blocks are shown as box-like structures made as hollow castings. The lower block 64 has ribs 65 on its outer face and perforations 66 for the passage of air. This hollow casting is fastened to the two lower tuyère plates by bolts 67. The casting has walls all around and receives air only 80 from a cored hole 68 in the wall adjacent to the tuyère plate. The upper end section is shown as made up of three hollow castings open at their bottoms. The castings 70 and 71 are provided with a ribbed structure similar to that of the plates 30, and they are fastened down in like manner by a hook bolt 73. These castings are bolted together by bolts 74. The end casting 76 is a simple hollow 85 structure bolted in place as illustrated. It will be understood that other forms of end structure may be employed with the tuyère plates. In the form shown, a blank 78 is employed at the lower end of the retort in 90 place of the corrugated bar 35, to cut down 95

the air supply at this point. It will be understood that such blanks may be used in other locations as well.

If one of the tuyère plates 30 requires placement, it is merely necessary to loosen or remove the nut 61 from the hook bolt 56 in that particular group, and then lift the tuyère plate vertically until the flange 50 will clear the lugs 48. The tuyère plate can then be tilted away from the furnace side wall until the shoulder 58 moves from under the rod 55, thus permitting removal of the plate. In inserting a new tuyère plate, the projection 53 is first placed in the opening 24. The rod 55 is then raised slightly by lifting an adjacent plate, and the new plate may then be tipped back towards the side wall of the furnace and dropped into place. The nut 61 may then be tightened, holding the tuyère 20 plates of the group firmly in position. In order to replace the corrugated plate 35, it is merely necessary to remove the plates 30 of the group located above plate 35. All of the parts are locked together when the bolts 25 are tightened, so that the tuyère construction is rigid during use.

Having thus described my invention, what I claim as new and desire to secure by Letters Patent is:

- 30 1. A side wall structure for an underfeed retort comprising a support, a set of narrow substantially vertical tuyère plates mounted on said support, each plate having a locking shoulder thereon, a fastening device including a rod releasably engaging the shoulders of a group of tuyère plates, and means including an adjustable member which is readily accessible from beneath said support for holding the rod against said shoulders and securing the plates to the support, said member being movable to release the rod so that any plate in the group may be removed independently of the others.
- 35 2. A furnace tuyère structure comprising a support, a group of substantially vertical air admitting tuyère plates mounted thereon, interfitting locating members on said plates and said support which hold the tuyère plates in position and prevent movement thereof in every direction except upwardly, each plate having a locking shoulder, a rod for the group, contacting with the shoulders of the plates, and a member engaging the rod and secured to the bottom of the support, said member holding the rod against the locking shoulders and being releasable to allow upward movement of the rod and individual removal of any plate in the group.
- 40 3. A furnace tuyère structure comprising a support, a series of air admitting tuyère plates mounted thereon and each having a fuel supporting flange and a vertical web provided with a substantially horizontal shoulder, interfitting locating members on said plates and said support which hold the

tuyère plates in position and prevent movement thereof in every direction except upwardly, a series of substantially horizontal rods each contacting with the shoulders of a group of tuyère plates, and means for fastening each rod independently to the support so that the rod may be released and moved upwardly and thus allow a plate in one group to be removed without loosening or disturbing a plate in another group.

4. An underfeed stoker comprising a retort side wall, a tuyère plate support mounted thereon, a series of air admitting tuyère plates mounted on said support and each having a fuel supporting flange and a vertical web provided with a shoulder, a series of substantially horizontal rods arranged so that each contacts with the shoulders of a group of tuyère plates, and a bolt for each group of tuyère plates fastened at its upper end to one of said rods and at its lower end to said retort side wall.

5. A high side wall tuyère plate for an underfeed stoker comprising a relatively thin vertical web, a steeply sloping flange arranged along one edge of the web and extending beyond each lateral face thereof which is adapted to contact with the fuel bed, and a rib arranged on each side of the web substantially parallel to the flange and spaced therefrom, said flange and ribs being provided with spaced notches to form air openings between adjacent blocks.

6. An air admitting plate for an underfeed stoker comprising a thin horizontal web, a pair of parallel ribs on the upper surface of the web, and a similar pair of parallel ribs on the lower surface of the web, each of said ribs having notches therein adapted to admit air to the fuel bed.

7. An air admitting plate for an underfeed stoker comprising a thin horizontal web, a pair of parallel ribs on the upper surface of the web, and a similar pair of parallel ribs on the lower surface of the web, each of said ribs having notches therein adapted to admit air to the fuel bed, and the notches in the lower ribs being staggered with respect to the notches in the upper ribs.

8. An air admitting plate for an underfeed stoker comprising a thin horizontal web, a pair of parallel ribs on the upper surface of the web, and a similar pair of parallel ribs on the lower surface of the web, each of said ribs having notches therein arranged at an angle to the ribs to direct air into the fuel bed.

9. A high side wall tuyère plate for an underfeed stoker adapted to be arranged parallel with similar plates above the retort wall and admit air to the fuel comprising a relatively thin vertical web having a steeply sloping flange along that edge which will contact with the fuel bed and a rib projecting laterally from the web which is spaced from

and is substantially coextensive with and parallel to the flange, both the flange and the rib providing air admitting passages, and the rib serving as a fuel support after the flange

5 has burned away.

10. A furnace tuyère structure comprising a support having a wall and a bottom provided with an opening therethrough, a separate tuyère plate disposed on the bottom on the opposite side of said opening from the wall, and a series of tuyère plates mounted side by side above said bottom tuyère plate which are supported on the top of the wall and rest upon the bottom tuyère plate in positions substantially perpendicular thereto, said parts forming a hollow structure adapted to support fuel against the tuyère plates and admit air thereto.

15 Signed at Worcester, Mass, this 23rd day
